UNITED STATES PATENT OFFICE.

CORNELIUS FLYNN, OF BROOKLYN, NEW YORK.

CAR-COUPING.

SPECIFICATION forming part of Letters Patent No. 293,442, dated February 12, 1884.

Application filed June 12, 1883. (No model.)

To all whom it may concern:

Be it known that I, CORNELIUS FLYNN, a citizen of the United States, residing in the city of Brooklyn, in the county of Kings and State of New York, have invented certain new and useful Improvements in Car-Couplings; and I hereby declare the following to be a full, clear, and exact description thereof, reference being had to the accompanying drawings, which form a part of this specification.

The object of this invention is to construct a car-coupler adapted to use the ordinary coupling-link in such a manner that the several devices or mechanisms for coupling and uncoupling cars shall be automatic in their operations, and so that each shall act independently of the others and remain passive when not performing its particular function.

My present invention is more especially designed to be an improvement on a certain car-coupling for which Letters Patent of the United States numbered 220,069 were granted to me September 30, 1879. In this improved car-coupling I retain and use the swinging frame described and claimed in the said Letters Patent, and my present improvements relate to the catch and other parts, as hereinafter particularly described; and this invention consists in the improved constructions and combinations of parts, as hereinafter specifically described and claimed.

In the accompanying drawings, Figure 1 represents a vertical longitudinal section of my improved car-coupler, taken through its center. Fig. 2 is an elevation of one of its sides, and Fig. 3 an elevation of its opposite side. Fig. 4 is a front elevation of one-half of the coupler, and Fig. 5 a plan view of a device for operating the levers to free the link.

Similar letters of reference indicate the same parts in all the several figures.

A represents the metal box in which the devices are held, which may be of suitable form and attached to the car in any suitable manner.

B is the swinging frame, (above mentioned,) to which is attached the swinging bolt B'; and C is the loose weight which serves to retain the said frame and the bolt in position when the cars are coupled or uncoupled, as the case may be.

t is a plate secured to one arm of the frame

B, against which the end of the link E strikes when it enters the box, and thus brings the bolt B' into the position shown in Fig. 1.

F is the catch which engages with the lower end of the bolt B'. This catch is secured upon a shaft, a, which has bearings in the sides of the box A, and is operated by the levers b, c, and d, the lever b being secured upon said shaft a. The end e of this catch, when in its normal position, is held, as shown in Fig. 1, to engage with the bolt B', the weight of the lever d tending to keep it in that position, and when said lever d is raised the catch is lowered and disengaged from the bolt. The levers b and c and the forward end of the lever d are inclosed within a box or compartment, f, the outer end of the lever d only being exposed.

In the drawings the outer plate of the box f (which said plate is detachable) is removed to show the arrangement of the levers. When the lever d is raised, said levers assume the positions shown by the dotted lines.

In Fig. 5 is shown a plan view of a device for operating the lever d. This consists of a shaft, g, which may be supported in any convenient position at the end of the car, (as for instance, underneath the platform,) upon which said shaft are fitted a fast pulley, h, and a loose pulley, i, and two hand-wheels, k k. A cord or chain, l, is attached at one end to the lever d and at its other end to the pulley h, so that by turning either one of the hand-wheels k the coupling can be disengaged by a person when standing on the ground. Another cord or chain, l', is attached to the loose pulley i, and passed upward to the top of the car, so that the coupling can be disengaged by a person when on the top of the car. A clutch, m, is also secured to the shaft g, to engage with the projection on the loose pulley i, so that the movement of the latter is independent of that of the pulley h.

I is a hook or stop for steadyng the link while the cars are being coupled. It is secured upon a shaft, n, that has bearings in the side of the box A, and is formed so as to press upon the rear end of the link, (when brought into the position shown in Fig. 1,) and thus, in connection with an inclined plate or bar, o, on the bottom of the box A, tends to depress the rear end of the link and correspondingly

raise the front end of the same, so that the latter is brought into position to enter the coupling-box of the car, to be attached at about its center. This hook I is operated by the levers *p*, *q*, and *r*, which are inclosed in a box or compartment, *L*, the detachable front plate of which is removed in the drawings in order to show the said levers. A pin, *s*, projecting through a slot in the front plate, is provided to on the upper end of the lever *p*, which is pushed forward to operate the levers by means of a hand-lever, *t*, that is pivoted to the box *A* or other suitable support in any convenient position. The under surface of the lever *q*, which comes in contact with the upper end of *p*, is formed substantially as shown in Fig. 3, so that the levers *p*, *q*, and *r* will be free to fall back into the positions shown by the dotted lines in said figure whenever the pressure of the lever *t* is removed, and the hook I will then be released from the link and brought into the position shown by the dotted lines *I'* in Fig. 1.

What I claim as my invention is—

1. The levers *b*, *c*, and *d*, inclosed within the box or compartment *f* and operated as described, in combination with the catch *F* and swinging bolt *B'*, as and for the purpose set forth. 25
2. The levers *p*, *q*, and *r*, inclosed within the box or compartment *L*, and constructed as described, in combination with the hook or stop *I* and link *E*, as and for the purpose set forth. 30
3. The hook or stop *I*, constructed as described, in combination with the levers *p*, *q*, and *r*, the inclined plate or bar *o*, and the link *E*, as set forth. 35
4. In combination with the levers *b*, *c*, and *d* and catch *F*, the shaft *g*, provided with the fast pulley *h*, and loose pulley *i*, and hand-wheels *k* *l*, the whole being constructed as described, to operate in the manner set forth. 40

CORNELIUS FLYNN.
